UNITED STATES PATENT OFFICE.

CLARENCE SLOCUM RICHARDSON, OF LOS ANGELES, CALIFORNIA.

SLUICE AND ORE CONCENTRATOR.

1,110,824.

Specification of Letters Patent. Patented Sept. 15, 1914.

Application filed August 26, 1913. Serial No. 786,686.

To all whom it may concern:

Be it known that I, CLARENCE S. RICHARDSON, a citizen of the United States, and a resident of Los Angeles, in the county of 5 Los Angeles and State of California, have made certain new and useful Improvements in Sluice and Ore Concentrators, of which the following is a specification.

My invention relates to ore concentrators, 10 my more particular purpose being to provide a concentrator suitable for either liquid or dry concentration—that is suitable for use with water or with air currents, as desired.

More particularly stated, my invention comprehends quite a number of improvements, the general purpose of which is to 15 improve the efficiency of apparatus of this kind.

Reference is made to the accompanying drawings forming a part of this specification, and in which like letters indicate like parts.

Figure 1 is a side elevation (parts broken 20 away) of the concentrator complete. Fig. 2 is a section on the line 2—2 of Fig. 1, looking in the direction of the arrow. Fig. 3 is a fragmentary section showing the feed roller at the bottom of the hopper. Fig. 4 is a view partly in section and partly in 25 fragmentary elevation reverse to the elevation shown in Fig. 1, disclosing the feed screen forming a part of the hopper, and means for agitating said screen. Fig. 5 is an enlarged fragmentary section of the 30 lower end of the sluice box, showing the gate for the same. Fig. 6 is a perspective of one of the removable riffle pans.

The trough or sluice box is shown at 7 35 and is supported by aid of posts 8 arranged in rows upon opposite sides thereof. A hopper is shown at 9, an engine or other motor at 10 and a pump at 11, the latter being preferably of the centrifugal type.

A platform or pier is shown at 12 and a car 13 rests upon this platform for the purpose of removing the refuse material after the latter is passed through the machine. A water pipe is shown at 14 and in 40 this instance is buried in the earth 15. This water pipe communicates with a body of water 16 and is provided with hand valves 17, 18, for controlling the supply of water. A pipe 19 is connected with the pipe 14 and 45 with the pump 11.

A flexible pipe section 20 is connected with this pump and with a distributing pipe 21, the latter being provided with a hand valve 22. A tube 23 is mounted upon the pipe 21 and extends upwardly therefrom, the upper end of this tube hooking over the top of the hopper 9. The tube 23 is used for supplying water into the hopper as the ore is fed thereinto.

A water motor is shown at 23^a and by 50 aid of belting 24, is connected with a pulley 25, the latter being mounted upon a shaft 26. This shaft carries a feed roller 27 of the form indicated in cross section in Fig. 3. The shaft 26 also carries a gear wheel 28, 55 located upon the opposite side of the hopper 9 from the pulley 25 and having the form indicated in Fig. 4. The gear wheel 28 serves the purpose of a sprocket wheel and is provided with a slideway 29. A slide 30 is fitted into this slideway and is connected 60 by a pitman 31 with a screen 32. This screen occupies the lower or discharge end of the hopper and is supported at one end by springs 33, as will be understood from 65 Fig. 1. As the shaft 26 is rotated, the slide 30 is shifted from one end to the other of the slideway 29, the adjacent end of the screen 32 being caused to reciprocate vertically.

The other end of the screen, being spring mounted, is agitated in a manner suitable for the purpose of distributing equally the ore particles as they drop upon and are 70 passed through the screen.

Engaging the gear wheel 28, is a sprocket chain 34. This sprocket chain engages a sprocket wheel 35, the latter being mounted upon a shaft 36. This shaft is journaled upon hangers 37 and carries another 75 sprocket wheel, the latter meshing with a sprocket chain 38. This sprocket chain meshes with a sprocket wheel 39.

In operative relation to the sprocket wheel 39 is a sprocket chain 40 which engages a 80 sprocket wheel 41. Hangers 42, 43, mounted rigidly upon the sluice box, are provided for supporting the sprocket chain last mentioned and the various sprocket wheels immediately associated with the same.

Two pendulum bars are shown at 44, 45. These pendulum bars are mounted upon cranks 46—47, the latter being carried by crank shanks 48, 49, which are journaled in the hangers 42, 43 and extend directly across 85 90 95 100 105 110

the sluice box. Carried upon the lower ends of the pendulum bars 44-45 are rake heads 50, 51, made preferably of structural metal and each carrying a number of short rake 5 teeth 52 as indicated more particularly in Fig. 2.

Suspension straps 53 arranged in pairs are secured to the bottom of the sluice box 7 and extend upwardly therefrom as indicated in Fig. 2. Each suspension strap 53 is at its top connected with a sliding frame 54, each sliding frame encircling one of the supporting posts 8. Connected with the sliding frames 54 are chains 55, the latter being partially wound upon drums 56. These drums are provided with hand cranks 57 whereby they may be turned so as to raise or lower the slides 54 and thus adjust the position of the sluice box.

Connected with the pipe 21 are a number of branch pipes 58-59 of different lengths, each branch pipe being provided with a valve 60.

A pitman 53^a extends from one pendulum bar 44 to the pendulum bar 45, and connects these bars together so that the pendulum heads 50-51 swing in unison. Engaging the pulley 25 is a belt 61 which leads to a pulley 62, the latter being mounted upon one end of a shaft 63, this shaft being supported upon bearings 64 carried by the posts 8.

Mounted upon the shaft 63 are two eccentrics 65, these eccentrics being provided with straps 66 which are secured to the adjacent side of the sluice box 7. As the shaft 63 is turned the eccentrics 65 cause the sluice box to sway back and forth in a direction crossing its general length.

One end of the sluice box 7 (see Fig. 5) is provided with boards 67 extending entirely across it and separated by a space 68. A sliding gate 69 may be adjusted into different positions between the boards 67 so as to regulate the depth of water and other material which may accumulate in the lower end of the sluice box. The bottom of the sluice box is shown at 70 and is adapted to hold a number of riffle pans 71, each having a substantially triangular form in cross section, as indicated in Fig. 5. The general shape of the riffle pans may be understood from Fig. 6.

A number of cylindrical casings 72 are severally provided with perforations 73, and are sunken partially into the bottom 70 of the sluice box. Located within each cylindrical casing 72 is a valve member 74 having a general cylindrical form and provided with a slot 75. The operator by turning any one of the valve members 74 relatively to the cylindrical casing 72 associated with it can control the discharge capacity of the two members considered collectively.

The riffle pans 71 are sunken into the bot-

tom 7 so as to be substantially flush with the upper surface thereof, as indicated in Fig. 5. The cylindrical casings 72 are connected with the various branch pipes 58-59 through which water is supplied continuously while the device is in action. Each drum 56 and hand crank 57 is mounted rigidly upon a shaft 76, the latter being supported by the posts 8. Each shaft 76 carries a ratchet wheel 78 secured rigidly upon it. Engaging this ratchet wheel is a dog 79, each dog being carried by the post 8, as will be understood from Fig. 2.

The water motor 23^a and the centrifugal pump 11 are of such structure that they can be used in connection with air, as well as water. When thus used the body of water 16 is discarded and air is drawn through the pipe 14 and discharged within the sluice box.

The operation of my device is as follows:— The parts being assembled and arranged as above described, and as shown in the drawings, the ore is fed slowly into the hopper 9 and the motor 10 is started into action. Power being communicated to the pump 11, the water is drawn into the pipe 14 from the body of water 16 and is forced upwardly through the flexible pipe section 20 and distributing pipe 21 to the various branch pipes 58-59, and thence into the valve members 74. The water thence escapes through the perforations 73 and spouts in various fine streams within the sluice box. As ore is fed into the hopper 9, it is brought into contact with water discharged into the hopper through pipe 23 and drifts downwardly upon the screen 32. This screen being in motion as above described, and the ore being fed downwardly by aid of the feed roller 27, first lodges upon the screen and is gradually sifted through the screen into the upper end of the sluice box. Here it is brought into contact with more water, which is spouted in fine streams from the perforations 73. The ore is thus carried downwardly over the riffle pans 71 which accumulate the concentrates.

The riffle pans are removable, and at intervals are taken out in order that the concentrates may be emptied into some appropriate receptacle. Rotation of the shaft 63 causes the eccentrics 65 to sway or swing the sluice box sidewise, as above described, this movement still further facilitating the lodgment of the concentrates within the riffle pans.

The rake heads 50 are alternately raised and lowered, and also swung sidewise by virtue of the action of the crank 46. These rake heads, actuated in this manner, are very useful in spreading out lumps of material which may otherwise tend to gather within the sluice box.

In order to adjust the general level of the

sluice box to elevate or lower either end independently of the other end thereof, the hand cranks 57 are employed as above described.

5 Sometimes it is desirable that a pool of water be formed in the lower end of the sluice box 7. For this purpose the gate 69 is adjusted by hand in order to prevent or restrict the escape of the water from the adjacent end of the sluice box. By virtue of the flexibility of the pipe section 20, the swinging motions of the sluice box do not interfere with the action of any of the gearing. Again, as all the gearing carried by 15 the sluice box is driven directly by the water passing through the flexible pipe section 20 and the distributing pipe 21, no source of power, other than the motor 10 employed to drive the pump 11, is needed for the purpose 20 of supplying energy to the machine.

I do not limit myself to the precise construction shown as variations may be made therein without departing from the spirit of my invention, the scope of which is 25 mensurate with my claims.

I claim:—

1. In an ore concentrator, the combination of a sluice box, means for suspending said sluice box in order to enable the same 30 to swing, a pipe for conveying water into said sluice box, said pipe having a flexible section, ore agitating mechanism carried by said sluice box, and mechanism controllable by the flow of water into said sluice box for 35 actuating said agitating mechanism.

2. An ore concentrator comprising a pump, means for actuating the same, a flexible pipe section connected with said pump, a distributing pipe connected with said 40 flexible pipe section, a sluice box carrying said distributing pipe, means for suspend-

ing said sluice box in order to enable the latter to be swung, a motor connected with said distributing pipe and adapted to be actuated by the flow of fluid therethrough, a feed roller mounted within said hopper, and connections from said feed roller to said motor for enabling said motor to actuate said feed roller.

3. An ore concentrator comprising a sluice box, means for mounting said sluice box so as to permit the same to swing, means for feeding ore and water into said sluice box, crank shafts supported by said sluice box and provided with crank pendulum bars 55 suspended from said cranks, a pitman connecting the pendulum bars, rake heads carried by said pendulum bars and located within said sluice box, and means controllable by the flow of the fluid into said 60 sluice box for actuating said crank shafts.

4. In a concentrator of the character described, a sluice box having a slanting bottom provided with a plurality of transverse grooves, and a plurality of riffle pans and 65 fluid supply pipes disposed in said grooves and alternating throughout the series thereof.

5. In a concentrator of the character described, a sluice box having a slanting bottom 70 provided with a series of transverse alternately wedge shaped and semi-circular grooves, riffle pans removably seated in the wedge shaped grooves, and valved fluid supply pipes disposed in the semi-circular 75 grooves and alternating with the riffle pans throughout the series.
